FIG. I

FIG. 2

FIG. 5

FIG. 6

FIG. 1 is a perspective view of a digital PABX desk console, showing our new design;

FIG. 2 is a top view thereof;

FIG. 3 is a front view thereof;

FIG. 4 is a back view thereof;

FIG. 5 is a left side view thereof; and

FIG. 6 is a right side view thereof.

The broken line disclosure of a telephone receiver and cord in FIG. 1 is for illustrative purposes only and forms no part of the claimed design. In FIG. 4 the connecting cable has been shown fragmentarily for convenience of illustration.

I claim:

The ornamental design for a digital PABX desk console, as shown and described.
